Attorney.

UNITED STATES PATENT OFFICE.

OBED H. MITCHELL, OF SPRINGFIELD, MISSOURI.

COMBINED CANT-HOOK AND LIFTING-JACK.

SPECIFICATION forming part of Letters Patent No. 298,765, dated May 20, 1884.

Application filed March 25, 1884. (No model.)

To all whom it may concern:

Be it known that I, OBED H. MITCHELL, a citizen of the United States, residing at Springfield, in the county of Greene and State of Missouri, have invented certain new and useful Improvements in Combined Cant-Hooks and Lifting-Jacks; and I do hereby declare the following to be a full, clear, and exact description of the invention, such as will enable others skilled in the art to which it appertains to make and use the same.

My invention is a new and useful combined cant-hook and lifting-jack, the object of which is to provide a simple, convenient, and strong device for raising, supporting, and handling heavy bodies, and for rolling logs, &c., by one man. These objects I accomplish by means of the device illustrated in the accompanying drawings, forming a part of this specification, 20 in which—

Figure 1 is a view in elevation of the entire device. Fig. 2 shows the cant-hook detached. Fig. 3 is a detailed view.

A is a standard or post, of any desired size 25 and of any suitable material. It has a foot, E, composed of two pieces, e e' , bolted to the sides at its lower end, to steady the same and to keep it from sinking into the ground. Beneath the front part of this foot E is secured 30 a toe-piece, J, made with a sharp edge, to prevent the device from slipping back when lifting, and especially when lifting railway-ties. In the front edge of the said standard are cut notches a' ; or a plate containing notches may 35 be secured to the same. In this standard are holes a , for adjusting the lever in height.

B is a lever composed of two pieces, b b' , which are secured to each other at the long end by any suitable device, as a bolt, b^4 , and 40 detachably secured on each side of the standard by a bolt or pin, b^3 , which is easily removed. Detachably connected with the long end of this lever is a supporting-rod, D, which is formed into a link, d d' , at its lower end to 45 encircle the standard and engage the notches a' , the upper end having a loop or a hook, d^2 , to engage a bolt, b^4 , so as to support a weight raised upon a hook, C, detachably secured to the short end of the lever.

50 G are plates secured to each of the pieces

b b' , and having an edge, g' , bent to fit over the upper edge of the said pieces at b^5 and b^6 , and to fit beneath the lower edge at b^2 . Through these plates are holes for receiving the bolts b^5 b^6 b^7 . These plates prevent the 55 lever from splitting and give the hook C the full strength of the lever.

C is a hook, having holes c , preferably made long and curved, as shown, and has a forked toe, c c' , for catching, holding, and 60 steady a log or tie while being raised and supported upon them, and the ends of the said toes are made sharp to catch the log when used as a cant-hook. The lever has holes for bolts b^2 b^6 , to attach the said hook when the 65 lever is detached from the standard, as shown in Fig. 2.

The device thus constructed may be used by one man for rolling and loading heavy logs upon a wagon. It may also be used as a 70 wagon-jack, and for raising ties of a railway and holding them up until they are clamped, and for other purposes.

Having thus described the construction, use, and operation of my invention, what I 75 claim as new, and desire to secure by Letters Patent, is—

1. A lifting-jack composed of a standard, A, having notches a' , holes a , and a foot, E, composed of two pieces, e e' , and having a 80 toe-piece, J, in combination with a lever, B, composed of two pieces, b b' , detachably secured to the said standard, and having holes for bolts b^2 b^5 b^6 , and a rod, D, which forms a link, d d' , and a hook, d^2 , and with a hook, C, 85 having holes c , and a forked toe, c c' , all arranged and constructed substantially as shown and described.

2. The combination of plates G, having the edge g' turned back, with a lever, B, composed of two pieces and having holes for bolts b^5 b^6 b^7 , and a supporting-rod, D, which has a link, d d' , and a hook, d^2 , a hook, C, which has sharp spreading toes c c' and holes c , together with a standard, A, having holes a , notches a' , 95 and a foot-piece, E, which has a toe-piece, J, all substantially as shown and described, for the purpose set forth.

3. The combination of a cant-hook composed of a lever, B, having holes for bolts b^2 b^5 b^4 100

b⁵ b⁶, and plates G, to which is detachably secured a hook, C, having holes *c* and toes *c'c'*, with a device composed of a standard, A, having holes *a*, notches *a'*, and a foot, E, composed of two pieces, *e e'*, beneath the front end of which is a toe-piece, J, and a rod, D, having a link, *d d'*, and hook *d'*, all arranged and constructed substantially as shown and described.

In testimony whereof I affix my signature in presence of two witnesses.

OBED H. MITCHELL.
